UNITED STATES PATENT OFFICE.

CHARLES T. NOYES, OF SACRAMENTO, CALIFORNIA.

OIL-BURNER.

No. 916,887.

Specification of Letters Patent. Patented March 30, 1909.

Application filed May 15, 1908. Serial No. 433,007.

To all whom it may concern:

Be it known that I, CHARLES T. NOYES, a citizen of the United States, residing at Sacramento, in the county of Sacramento and State of California, have invented new and useful Improvements in Oil-Burners, of which the following is a specification.

My invention relates to oil-burners.

The object of the invention is to provide a simple, cheap, practical oil-burner for use in furnaces, forges and the like, and particularly designed for use with low pressure fanned air ordinarily used in blacksmith shops.

The invention consists of the parts and the construction and combination of parts as hereinafter more fully described and claimed, having reference to the accompanying drawing, in which the figure is an elevation in partial section of the burner as applied to low pressure air.

The burner may be built with ordinary pipe and pipe fittings.

A represents a T closed at one end by a plug 2, except for the oil pipe 3 which is tapped into the plug and connects with any suitable source of supply. A short tube section 4 screws into the other end of the plug in continuation of the oil pipe 3, and this section 4 continues through the T and is arranged concentric with the outside tube 5, which latter is tapped into the front end of the T. Preferably the front end of the air tube 5 is contracted, as shown. The end of the oil tube 4 screws into a tip or cap 6 which has its outer end approximately flush with the end of the air pipe 5. This cap 6 has a chamber 7 into which the oil pipe 4 opens, and this chamber 7 has a series of oil outlets 8 which are inclined forward toward the discharge end of the burner, and open into the longitudinal grooves 9 on the periphery of the larger diameter of the cap.

The oil in flowing out through the ducts 8 runs in the same general direction with the

flow of the air in the outer tube, and is thus more readily acted upon by the air; in fact, the air in passing the openings serves to create a suction which promotes a steady flow of the oil.

The grooves 9 which are made in the enlarged portion of the tip are expanded and deepened at their outer ends, which construction tends to converge the jets of atomized oil toward the center and commingle them into one common flame.

Air under pressure from any suitable source of supply enters the burner through the air pipe 10.

Having thus described my invention, what I claim and desire to secure by Letters Patent is—

1. An oil burner consisting of concentric oil and air pipes, the oil pipe being arranged within the air pipe and provided with a tip having forwardly and outwardly inclined oil ducts communicating with the oil passage in the oil pipe, and longitudinal passages in the tip intersected by the oil ducts and having their forward ends converging toward the axis of said tip.

2. An oil-burner consisting of concentric oil and air pipes, the oil pipe being arranged within the air pipe and provided with a tip having forwardly and outwardly inclined oil ducts communicating with the oil passage in the oil pipe, said ducts intersecting longitudinal peripheral grooves on the tip, and said peripheral grooves being deepened at their forward ends whereby the jets of atomized oil are made to converge toward the axis of the tip.

In testimony whereof I have hereunto set my hand in presence of two subscribing witnesses.

CHARLES T. NOYES.
